METHOD FOR THE TREATMENT OF HEAVY HYDROCARBON MATERIAL

Application filed June 6, 1929. Serial No. 368,997.

This invention relates to a new and improved method for the treatment of heavy hydrocarbon material in liquid form, and more particularly to a method of treatment adapted for use with the heavy residues of various distillation and cracking processes.

This invention relates to the better utilization of heavy residues obtained from modern cracking stills and from the distillation of oils containing high percentages of asphalt, as for example, oils of California and Mexico.

The specifications for fuel oil usually limit the amount of free carbon and also the viscosity of the oil in such a way that unless the cracking process is stopped well within its possible range, these specifications cannot be met. This is also true of heavy asphaltic residues or oils.

By our method we propose to take the heavy residues or oils and heat them to a high temperature such as for example, 800° F. to 1000° F. depending on the quality of the stock. The operation is to reduce the formation of vapors in the heating coils to the extent that the carbon will not separate out enough to cause trouble in the coils.

In place of the usual flash chamber we propose to release the pressure and thus complete the vaporization of the material practically either within a coking oven or in proximity to it in a column which may be superposed thereupon and in direct connection therewith. The purpose of this method is to allow the heavy residue which is formed from the primary heating to be deposited in a coking chamber in such way that further distillation can take place and the final residue be coked. By this method of operation the lighter fractions formed can pass off without being heated by the heat of the coking operation beyond that extent which may be desirable and at the same time the non-volatile portions can reach the heating area and be cracked and distilled before the coke is actually formed.

In one method of operation the heavy portion will be deposited upon a horizontal floor made up of either refractory material or special alloys suitable for the purpose, and heated from below. In order to obtain a uniform

quality of coke it is necessary to maintain a liquid layer on top of the coke in order to distribute the residue evenly over the floor of the oven and also to make it possible to further crack this material without overheating. 55

It is an object of the present invention to provide a new and improved method for the treatment of heavy hydrocarbon material in liquid form.

It is a further object to provide a method 60 in which distillation and cracking are carried out to a point where the solid residue of the process is a merchantable coke.

It is an additional object to provide a method 65 in which the coke made from the solid residue may be of a character and density suitable for metallurgical purposes.

It is also an object to provide a method of treatment wherein the process is carried on with comparatively simple apparatus and in 70 a manner adapted for commercial production.

It is a further object to provide a method wherein the material being treated is maintained under such pressure and/or velocity 75 during its passage through heating coils, that the solid matter and carbon suspended therein is not thrown down to clog the pipes.

It is an additional object to provide a method wherein the oils and volatiles recovered are not subjected to destructive heat after 80 their liberation.

Other and further objects will appear as the description proceeds.

We have shown in the accompanying drawing somewhat diagrammatically, one form of 85 construction adapted for carrying out our improved method of treatment. In the drawing—

The single figure is a diagrammatic vertical section of the apparatus. 90

The oven or coking chamber 11 is provided with a floor 12 of heat resistant material, and a plurality of heating flues 13 are provided extending below the floor. These flues 13 are connected through passages 14 with regenerators 15 through which pass the air and fuel for combustion in the flues. The lower pass 16 of these regenerators is connected by passages 17 with the cross flue 18. This flue 18 leads through passage 19, controlled by valve 95

20, to a stack 21. The other end of the flue 18 is shown as connected by passage 22, controlled by valve 23, with the preheater 24. The stack 25 leads from the heat exchange apparatus 24.

5 The inlet pipe 26 for the material to be treated, leads to the interior pipes 27 of the preheater 24 and these pipes 27 are connected through a header to the outlet pipe 28. The 10 baffles 29 are provided in the preheater 24 for the purpose of causing the hot gases to take a tortuous passage. The pipe 28 leads from the preheater 24 to the upper chamber 30 which is superposed on the coking chamber 11 and in communication therewith. The 15 pipe 28 is provided with the pressure reducing valve 31 and with the discharge nozzle 32, the latter being located in the chamber 30.

The chamber 30 is provided with a plurality of sloping baffles 33 adapted to cause the 20 gases passing through the chamber to take a tortuous passage and to bring them into intimate contact with the liquid passing down through the chamber. The lower end of the 25 chamber 30 is provided with a damper 34 which, in its open position, as shown in the drawing, serves to receive the liquid from the lowermost baffle 33 and to permit it to drop to the floor 12 of the coke oven 11. 30 When moved to horizontal position the damper 34 closes off communication between the chamber 30 and the coke oven 11.

The top of the chamber 30 is connected by 35 passage 35 with the cooling apparatus or condenser 36. This apparatus 36 is provided with the pipes 37 through which cooling water may be passed by means of the inlet pipes 38 and discharge pipe 39. The chamber 36 is provided with the outer passage 40 for carrying off gases or vapors which are not condensed in the apparatus.

The condensate in the chamber 36 is collected in the conical bottom portion 41 and withdrawn through pipe 42, which leads to the 45 pump 43. The pump 43 discharges into pipe 44 which pipe is provided with a branch 45 controlled by valve 46 which branch may lead to any desired apparatus for storing or using the liquid. The pipe 44 is also provided with a second branch 47 controlled by valve 48, this branch leading to a distributing nozzle 49 located in the chamber 30.

In carrying out our improved method by 55 means of the apparatus shown, the floor 12 of the coking chamber 11 will be brought to a coking temperature by means of combustion taking place in the flues 13 under the floor. The air and fuel for the combustion may be preheated in a second series of regenerator chambers 15, not shown. The heated products of combustion will pass down through the regenerators 15 and 16 and passages 17 to the flue 18. From this flue a portion of the hot gases may be led off through stack 21 and another portion led through the preheater 24

to the stack 25. By controlling the distribution of the gases to the stack 21 and the preheater 24, any desired amount of heat may be transmitted to the material being treated in the preheater.

70 It will be understood that different types of preheaters may be used and the passages and pipes may be arranged on the counter-current principle. Additional direct heaters may also be used if desired.

75 The material being treated, which will be heavy hydrocarbon matter, in liquid form, will be introduced into the apparatus shown, through the pipe 26. It will be understood that this material may be previously treated 80 in any desired form of cracking or distilling apparatus or other apparatus for the treatment of such hydrocarbons. When it reaches the pipe 26 it will be under pressure and may be already heated. Its temperature 85 will be raised in the pipes 27 in the preheater 24 and it will pass up through pipe 28 to the pressure reducing valve 31. It will be understood that the material will be under such pressure and/or velocity in the pipes 90 26, 27 and 28 as to prevent the separation of any vapors or volatilized fractions to such an extent as will permit the throwing down or deposition of entrained carbon or other 95 heavy material likely to clog the apparatus. By means of the valve 31 the pressure will be suitably reduced and the material will be sprayed into chamber 30 through the nozzle 32.

100 Due to the reduction of pressure there will be a substantial instantaneous vaporization and release of gases and vapors in the chamber 30 which gases and vapors will ascend through the chamber and be drawn off through passage 35. The liquid residue will 105 be deposited onto the inclined baffles 33 and will run down these baffles and drip from their edges, eventually being deposited upon the floor 12 of the coking chamber. During the flow on the baffles 33 and the drip from baffle to baffle, the liquid will be exposed to the action of the ascending gases and vapors. Cracking and vaporization will take place on the floor 12, the gases and vapors ascending through the chamber 11 and chamber 30 and passing off with the gases and vapors from the discharge nozzle 32. The 110 rate of deposit of the liquid residue on the floor 12 will normally be so regulated as to maintain a thin liquid layer on top of the coke layer being formed on the floor. This thin liquid layer insures the deposition of a substantially uniform layer of coke throughout the floor area.

115 The gaseous products of the process passing off through passage 35 are partially condensed by the cooling coils 37 in the condenser 36, the outlet gases passing off through passage 40 to additional condensers and any suitable gas holding or using apparatus. 120 125

The liquid condensate collected in the lower portion 41 of the apparatus 36 may be partially returned to the chamber 30 for control and/or further treatment. The quantity of 5 this return will be regulated by means of the valves 46 and 48.

The process will be periodically interrupted, the damper 34 being turned to close off the upper chamber or tower 30 from the cooking chamber 11. During this period of interruption the ends of the coking chamber 11 will be opened and the layer of coke formed in the chamber will be removed. It will be understood that the flow of liquid material 10 into the chamber 30 may be interrupted some time prior to the closing of the damper 34 if desired, and the coking continued in the chamber 11 to completely coke the liquid material 15 layer then remaining on the coke. After the coke has been removed the damper 34 may be 20 opened and the process continued.

It will be understood that the showing in the drawing is somewhat diagrammatic in character. In one specific example of carrying 25 out the method the heavy liquid was at a temperature of 500° F. at the pump which forced the liquid through an extended pipe line to the coils, the pressure being 350 pounds per square inch at the pump. The pressure 30 was 325 pounds per square inch at the beginning of the hot coil and dropped to 175 per square inch at the outlet of the coil. The temperature was 800° F. at the point of discharge into the coking chamber. The coil 35 consisted of 310 feet of 1½ inch pipe and 230 feet of 1 inch pipe. The coil served to raise the temperature from 500° to 800° F.

While we have shown somewhat diagrammatically one form of apparatus adapted for 40 carrying out our invention and described certain methods of carrying it out, it is to be understood that our invention may be carried on in other forms of apparatus and that it is capable of changes and modifications to 45 meet varying conditions and requirements, and we contemplate such changes and modifications as come within the spirit and scope of the appended claims.

We claim:

50 1. The method of converting heavy hydrocarbons in liquid form into lighter hydrocarbons and coke in a chamber having a flat floor heated from below which comprises raising the hydrocarbons to a high temperature 55 while flowing in a stream under a pressure sufficient to prevent undue vaporization, releasing the pressure, removing vaporized hydrocarbons and discharging the unvaporized hydrocarbons directly onto the heated 60 floor of said chamber or onto the coke deposited thereon by the cracking and vaporization of the unvaporized hydrocarbon, and further removing vaporized lighter hydrocarbons.

65 2. The method of converting heavy hydro-

carbons in liquid form into lighter hydrocarbons and coke in a chamber having a flat floor heated from below which comprises raising the hydrocarbons to a high temperature while flowing in a stream under a pressure sufficient to prevent undue vaporization, 70 releasing the pressure, removing vaporized hydrocarbons and discharging the unvaporized hydrocarbons directly onto the heated floor of said chamber or onto the coke deposited thereon by the cracking and vaporization of the unvaporized hydrocarbons, and further removing vaporized lighter hydrocarbons, the flat floor being heated to a temperature sufficient to crack the unvaporized 75 hydrocarbons and reduce the residue to a layer of hard, metallurgical coke.

3. The method of converting heavy hydrocarbons in liquid form into lighter hydrocarbons and coke in a chamber having a flat floor 80 heated from below which comprises raising the hydrocarbons to a high temperature while flowing in a stream under a pressure sufficient to prevent undue vaporization, releasing the pressure, removing vaporized hydrocarbons and discharging the unvaporized hydrocarbons directly onto the heated floor of 85 said chamber or into the coke deposited thereon by the cracking and vaporization of the unvaporized hydrocarbons, further removing vaporized lighter hydrocarbons, the flat floor being heated to a temperature sufficient to crack the unvaporized hydrocarbons and reduce the residue to a layer of hard, metallurgical coke, and condensing heavier fractions 90 of the vapor from the chamber and returning them to the chamber for further cracking 95 treatment.
